UNITED STATES PATENT OFFICE.

GILBERT C. WHITNEY, OF NEW YORK, N. Y.

TRAIN-INDICATION SYSTEM.

Application filed March 27, 1924. Serial No. 702,262.

This invention relates to train describers and train indicators in general wherein means are provided to indicate the position or describe the movement of a train on a railway track and in particular to novel means for accomplishing the aforementioned results with a minimum of expense both as to first cost and maintenance.

It is the general custom on railroad systems to install means whereby the position of a train may be known at some selected point, such, for example, as the tower from which switches and signals are controlled, or despatcher's headquarters where it is a desideratum in the proper maintenance of train schedules. This means sometimes takes the form of audible indicators, such as bells, track relay indicators, electric lamps and the like and when electric lamps are employed they are generally of miniature size and allocated in a track model. When so assembled they form what is termed an illuminated track indicator, etc., etc. The information as to the occupancy of the track, however repeated or exhibited at the selected point, is generally obtained from a contact of a track relay or repeater and the circuit controlling the track indicator is influenced by the track relay as will be appreciated. Since the track relay is a component part of the well known track circuit, the rail section of which varies in length and very often reaches a length of one mile, and since the track relay is generally limited to three positions and customarily installed to operate in two positions, it is apparent that, at best, the track relay and consequently any train indicating or announcing means controlled thereby is a track section indicator; but, even this is only presumptive because the presence of a train on a track circuit is not essential to the operation of the track relay. To overcome the foregoing defect, to accomplish the same without moving parts, and to, in some instances, eliminate the use of insulated track rail joints are general objects of this invention and additional objects will be disclosed as the specification proceeds and I will point out the novel features in the appended claims.

In my co-pending application, Serial No. 697,129, I have disclosed the same principles as hereinafter set forth but as applied to railway traffic controlling systems.

55 I have provided six figures on the accom-

panying drawing to clearly set forth the application of my invention to present day track circuit design and an installation for use in non-signalled territory to indicate train movement therein. Fig. 1 shows the main element of my invention arranged to provide indication as to the presence and movement of a train along a specified track section and wherein said train presence and movement is indicated by the appearance or variation in brilliancy of an electric lamp or other similarly characterizable means in the indicator system; Fig. 2 is similar to Fig. 1, except that train presence in the track section is presumed due to the fact of disappearance of the electric indicator lamp or other characterizable means but Fig. 2 does not provide for indicating train movement; Fig. 3 is similar to Fig. 1 with the addition of means intermediate in the track section for contrasting characterizable effects in the indicator system; Fig. 4 is similar to Fig. 1 except, that audible indication is given when the train enters the track section and the electro-magnetic indicator follows through in synchronism with the train in the track section; and Fig. 5 shows a section of track without insulated joints and which has the principle of my invention applied for indicating presence and movement of the train—the individual indicator apparatus in the tower or at the selected point being identical with that shown in Figs. 1, 2 and 3. Fig. 6 is a diagram associated with Fig. 5 to illustrate the performance of the indicator lamp relatively to the position and movement of a train on the track section. Similar elements and parts are designated by the same characters in all of the figures.

Referring to Fig. 1, a track section is set apart by insulated joints 8—the track rails of the section being identified by the reference characters 6 and 7. At one end of said track section a transformer 9 is shown connected to track rails 6, 7, by means of track wires 10, 11, resistance 12 and fuse 13. Transformer 9 is the medium, when energized by means of wires 14, 15, from power wires 16, 17, connected to the source of energy alternator 18, by which appropriate current supply, when a train is not present, is transmitted over track rails 6, 7 to track wires 19, 20, fuse 21 and resistance 22 to winding 23 of relay 24. Winding 25 of relay 24 receives energy by means of wires

26, 27, from power wires 16, 17, and thus far the whole constitutes the well known alternating current track circuit wherein most of the energy required for the operation of the track relay 24 is supplied locally and only a small part or activating current is transmitted over the track rails. Also in conventional manner I have shown signal 32-33 controlled by contact 28 of track relay 24 and control wires 29, 30 and 31. The track and circuit and signal and circuit design outlined above is intended simply as a structure and I make no claims of invention in connection therewith—it is shown only 10 to provide a basis for suitably illustrating my invention.

This invention consists in connecting the primary winding 35, of transmitter transformer 34, in multiple with resistance 12, 20 as shown, and so that part of the current flowing to winding 23 of relay 24 passes through said winding 35. Inductively coupled to winding 35 is shown secondary winding 36 and the current induced therein is 25 carried over transmission wires 37, 38, to the tower or other selected point and there energizes winding 40 of transformer 39. Inductively coupled to winding 40 is shown secondary winding 41 and the current induced therein becomes available and is used 30 for energizing indicator lamp 42 or other similarly appropriate means as will be appreciated. When the track section is not occupied by a train winding 23 and resistance 35 35 are included in series in the circuit receiving current which passes from transformer 9 and through winding 35, but when a train enters the track section the wheels of the train, having negligible resistance, 40 shunt out said winding and resistance and due thereto more current flows from transformer 9 via winding 35. The increased rate of current flow varies depending upon the position of said train in the track section, being lowest when the train is furthest 45 distant from transformer 9, because of the resistance of the track rails 6, 7 as will be appreciated. From the above it will be clear that the current flow in the transmission circuit 37, 38, and consequently illumination of indicator lamp 42 will be least 50 when said track section is not occupied and will variably increase with the entrance onto and passage of the train along toward the transformer end of said track section.

I am aware of the fact that it is not novel, in a signal system, to utilize the increase in current flow in a track circuit, when it becomes occupied by a train, to control a signal lamp and, therefore, my invention does not reside in the fact that my system provides similar control, by my invention does reside in the fact that I have provided a system which makes use of the above mentioned control for train indication purposes

and also whereby the variation in current flow resulting from the train occupying various positions on the track rails of the track section is an indication as to the comparative position and movement of the train on 70 the track section.

From the foregoing, it will be evident that a low voltage must be applied to the track rails of the track circuit because of the leakage through the ties and ballast. Now, as 75 has been explained, it is customary to transmit the indication to a central point, such as a despatcher's headquarters, and the successful system must cover a considerable territory, and, owing to the great number of 80 circuits involved, economy demands that small wires be used in the transmission circuit and naturally only a small transmission current can be tolerated, otherwise the loss in transmission would not only be prohibitive, but would otherwise interfere with the indication, as will shortly be explained. Starting, then, with the necessarily low track circuit voltage I provide inductive 85 coupling 34 to act as a step-up transformer to provide a higher transmission circuit voltage and the corresponding transmission current for indication purposes is of the order of 0.015 ampere and less. Now, as is well-known, an indication lamp of high voltage 90 and low wattage (one watt and less) is not commercially possible because of the inability to provide a lamp filament which will heat on a current flow of the above mentioned order of 0.015 ampere and less and accordingly I provide receiver transformer 39 of the step-down type and wherein the resultant induced indicating current flow to lamp 42 is of the order of 0.080 to 0.0350 95 ampere and at an operating voltage of from approximately one (1) volt to five (5) volts. Thus, it will be evident that, in the use of the receiver transformer (39), means have been provided to effect an indication on a 100 very small transmitted power and with a minimum in the losses incident to transmission. A minimum in the losses during transmission is important for the reason that the variation in track circuit current flow, as 105 between the train or car at one end of the track section and at the other end of the track section, is small and every last effort must be made to conserve the results, of the variation, during transmission to the indication device.

In Fig. 2, I have shown my invention arranged to indicate the condition of the track section in a different manner:—with the track section unoccupied the indicator lamp is arranged to be lighted and when a train enters upon the track section winding 35 of the transmitter transformer 34 has its current supply reduced by virtue of the train wheel shunt and consequently the illumination 115 of indicator lamp 42 is reduced. It 120 125 130

should be obvious that, as arranged in Fig. 2, indication of movement as the train passes through the track section cannot be had.

In Fig. 3, I have shown the system illustrated in Fig. 1 supplemented by a resistance 43 introduced into the track section to provide means for a distinct contrast in the indicator system when the train passes insulated joints 8^a. When installed thus indicator lamp 42 is arranged to indicate occupancy and movement in the first portion of said track section at not over 50% illumination of said indicator lamp 42 and passage of train into and along the second portion is indicated by increase of illumination between 50% and 100% as will be appreciated. Obviously, I may install a plurality of resistances 43 or reactances at suitable points and thus provide a plurality of distinctly contrasting indicating points. I provide transposition of track circuits whenever I install distinct contrasting points to insure that the track relay of the section, when installed, will be open if any insulated joints 8^a break down.

In Fig. 4, I have shown the system illustrated in Fig. 1, but with an electromagnetic visual indicator 44 supplemented by an audible indicator, in this instance a bell, 45 in place of indicator lamp 42 of Fig. 1. Indicator 44 is biased to the position A and the bell 45 is arranged to be silent when the track section is not occupied. On the passage of a train onto the track section the increased current flow due to the train wheel shunt causes increased induced current to flow in the transmission circuit 37, 38, and hence increased current flow to the bell and indicator 45, 44. Said increased current flow to the bell and indicator causes the bell to sound single stroke or continuous and at the same time the movable portion 47 of indicator 44 moves through the space 46 to eventually arrive at position B—this movement, however, is arranged to be synchronous with the passage of the train through the track section and is brought about by the variation in current flow due to the train wheel shunt in its movement along the track section varying the resistance of the circuit of which the track rails 6, 7, form a part as will be appreciated. It should be noted that movable portion 47, in practice would not be exposed to view in the space 46 unless a train is present on the track section. It should also be noted that bell 45 may be placed in series in the circuit of indicator 44.

In Fig. 5, I have shown my invention arranged in a system of train indication and without the use of insulated joints. Track rails 6, 7, are shown continuous and I have shown three transformers 9 to supply current to the track at selected points, approximately though not necessarily equi-

distant. Said transformers 9 receive energy from source of energy supply alternator 18 by way of power wires 17, 16, and branch wires 15, 14. The secondary windings of transformers 9 are connected to the track rails 7, 6, by means of track wires 11, 10. Connected in series in each of the secondary windings I show primary windings 35 of transmitter transformers 34 and inductively coupled to said primary windings I show transmitter secondary windings 36, each of which is included in a transmission circuit 37, 38. Included at the receiver end of said transmission circuits I show, inductively coupled thereto, indicator lamps 42—the receiver end of these transmission circuits are identical in principle with that described in connection in Fig. 1. I show track rails 6, 7, short-circuited by reactances C, D, and E at suitable places between the points where current supply track wires 10, 11, are connected to said track rails. The characteristics of all inductive apparatus are proportioned such that the current supplied to the respective indicator lamps 42 is a maximum when the track rails 6, 7, are short-circuited, as by a train wheel shunt, at the corresponding points of current supply track wires 10, 11 and said maximum condition varies as said train wheel shunt moves either way from said points with slow reduction until said train wheel shunt passes a track short-circuiting reactance and thereafter at a rapidly increasing rate, as illustrated in Fig. 6 and wherein a train is assumed to be a point only for the purpose of clarity. Referring to said diagram:—the solid irregular line traces out the value of current supply to indicator lamp 42CD as the train wheel shunt approaches and traverses track section CD reaching a maximum when the train wheel shunt is adjacent track wires 10, 11, for that section and reaching a practical minimum rapidly when and as said train wheel shunt passes a very short distance outside of said track section;—similarly, the dot and dash line illustrates similar conditions for the track section and corresponding indicator lamp DE and so on to the end of the system. Obviously, a train is not a point and the representative lines in the diagram will broaden and overlap in the proportion that said train point takes on the dimension, length.

Attention is directed to the following facts:

1st. That in several installations, I have used 1 watt indicator lamps, and consequently have been successful in using small inexpensive transformers and further owing to the small amount of power transmitted my system makes use of small gauge transmission wires (No. 19 A. W. G. and smaller) with the economic result that my system is extremely cheap to install.

2nd. That I may interchange the several elements of the several figures, for example, I may use the electromagnetic and/or audible indicator of Fig. 4 in the system of Fig. 1.

3rd. That, whereas means in the form of an impeding element (for example resistance 12, Fig. 1) are required to prevent the train wheel shunt being a short circuit on transformer 9 the same may be eliminated and the function performed by winding 35 of transformer 34 (see Fig. 5) in which event the energy required for the operation of my system is that which would otherwise be dissipated in the form of heat in the impeding element and therefore when thus arranged no additional power equipment or expenditure for current supplied is required.

4th. That my system operates with a minimum of parts and thus to effect a minimum of expense in maintenance cost.

5th. That the current flow in the inductive coupling 35, 36, is variable and proportionable to the position of the train in the track section, that is, the current flow due to the train wheel shunt varies and has a different value as the train proceeds through said track section.

6th. That, although the voltage which can be applied to the track rails is limited to a low value, as in present day track circuits, on account of ballast leakage, my system lends itself very readily for train wheel control of high power circuits and without moving parts.

7th. That the track relays or other devices and elements, to which current is transmitted may be termed receiver devices, or receivers.

8th. That the indication is responsive to the movement of the train.

9th. That track reactances C D E (Fig. 5) may be eliminated in which event the operation of my system will still be effective but less contrastly distinctive.

10th. That transmitter transformer 34 may be included in series in the primary circuit of transformer 9 instead of the secondary circuit thereof.

11th. That the system of Fig. 5 is effective regardless of the direction in which the train moves.

12th. That, given the length of train and track section, the time of transit of member 47 of indicator 44 (Fig. 4) is a function from which train speed may be determined.

13th. That the system of Fig. 1 is not dependent, for its indication operation, on the installation of a track relay or other apparatus at the opposite end of the track circuit.

14th. That my system may be incorporated into or inductively coupled to many forms of existing alternating current track circuits

with a minimum of expense and exchanging of apparatus.

Obviously, various types of track circuits, both alternating and direct current, of the single and double rail type may be employed in combination with my invention by making the obvious appropriate changes well known to any one ordinarily skilled in this art and I desire to have it understood, therefore, that the arrangements and illustrations which I have shown and described are merely illustrative and do not exhaust the various embodiments and forms which my invention may take in general practice.

Having thus described my invention I claim and desire to secure by Letters Patent:

1. In a train indication system, a track circuit including a source of energy, and indication means inductively coupled to said track circuit, said indication means synchronously indicating the movement of a train on said track circuit.

2. In a train indication system, a track circuit including a source of energy and indication means, said means indicating the movement of a train on said track circuit by comparative variation in the energization of said means.

3. In a train indication system, a track circuit including a source of energy, and remotely located indication means synchronously responsive to the movement of a train on said track circuit.

4. In a train indication system, a track circuit including a source of energy, a transmission circuit, and indication means, said transmission circuit inductively coupled to said track circuit and said means inductively connected to said transmission circuit.

5. In a train indication system, a track circuit including a source of energy, and a remotely located indicator lamp inductively coupled to said track circuit and comparatively indicating the position of a train on said track circuit.

6. In a train indication system, a track circuit including a source of energy, and an indicator lamp inductively coupled to said circuit for indicating the movement of a train on said track circuit by increase in brilliancy of said lamp.

7. In a train indicating system, a track circuit including a source of energy, an impeding element in series with the energy supply to said track circuit, an inductive coupling in multiple with said element, and an indicator lamp inductively coupled to said circuit and indicating the movement of a train on said track circuit by variation in illumination of said lamp.

8. In a train indicating system, a track circuit including a source of energy, an impeding element in series with the energy supply to said track circuit, an inductive cou-

- pling in multiple with said element, and an indicator lamp inductively coupled to said inductive coupling and indicating the movement of a train on said track circuit by a gradual decrease in light emitted by said lamp.
9. In a railway traffic controlling system, a track circuit including a source of energy, and a remotely located indicator lamp inductively coupled with said circuit, said lamp without illumination when the track circuit is unoccupied and with illumination when said track circuit is occupied, said illumination gradually increasing or decreasing according as the train moves in one direction or the other on said track circuit.
10. In a railway traffic controlling system, a track circuit including a source of energy, and a remotely located indicator lamp inductively coupled with said circuit, said lamp illuminated when the track circuit is unoccupied and with increased illumination when said track circuit is occupied.
11. In a train indication system, a track circuit including a source of energy, an indication transmitter connected in series with said source, and an indication receiver inductively coupled to said transmitter and adapted to comparatively indicate the distance between a car on said track circuit and the point where said energy is connected to said track.
12. In a train indication system, a track circuit including a source of energy and a track transformer, an impeding element connected in series with said circuit, a second transformer connected in multiple with said element, a third transformer connected with the second transformer, and indication means connected with the third transformer, said third transformer and indication means remotely located from said second transformer.
13. In a train indication system, a track circuit including a source of energy and a track transformer, a second transformer connected in series with said circuit, a third transformer connected in series with the secondary of the second transformer, and indication means connected in series with the third transformer, said third transformer and indication means remotely located from said second transformer.
14. In a train indication system, a track circuit including a source of energy and a track transformer, a second transformer connected in multiple with the second transformer and indication means connected in multiple with the third transformer, said third transformer and indication means remotely located from said second transformer.
15. In a train indication system, a track circuit including an alternating current source of energy, and remotely located indication means inductively coupled to said track circuit, said means indicating the presence of a train on said track circuit and sensitive to indicate a plurality of positions of said train during its movement on said track circuit.
16. In a train indication system, a track circuit including an alternating current source of energy, and remotely located indication means inductively coupled to said track circuit, said means indicating the presence of a train on said track circuit and sensitive to continuously indicate the movement of said train during its progress on said track circuit.
17. In combination, a track circuit including the track rails of a railway track section and an alternating current source of energy supply for said track circuit, and indication means responsive to variations of energy flow in said track circuit as between a track section unoccupied and occupied by a car, said indication means sensitive to indicate variations in the energy flow in the track circuit as the car moves on said track section.
18. In combination, a track circuit including the track rails of a railway track section and an alternating current source of energy supply for said track circuit, and indication means responsive to variations of energy flow in said track circuit as between a track section unoccupied and occupied by a car, said indication means sensitive to indicate variations in the energy flow in the track circuit according as the car occupies one position or another on the track section.
19. In combination, a track circuit including the track rails of a railway track section and an alternating current source of energy supply for said track circuit, and an indicator lamp constantly energized and responsive to variations of energy flow in said track circuit as between a track section unoccupied and occupied by a car, said indicator lamp sensitive to indicate variations in the energy flow in the track circuit according as the car occupies one position or another on the track section.
20. In combination, a track circuit including the track rails of a railway track section and an alternating current source of energy supply for said track circuit, and an indicator lamp responsive to variations of energy flow in said track circuit as between a track section unoccupied and occupied by a car, said indicator lamp with partial illumination when the track section is occupied and with variable degrees of brilliancy in synchronous response to variations in the energy flow in the track circuit, the last mentioned variations resulting in accordance with change of car position on the track section.

21. In a train indication system, a section of railway track adapted to be traversed by an electric current, a source of alternating current supply connected to the rails at one end of said section and supplying said electric current to said track circuit, an inductive coupling connected in series with said source, and an indicator lamp connected to said inductive coupling and adapted to comparatively indicate the distance between a car at any point on said section and said end of said section.

22. The invention set forth in claim 21, with the indicator lamp inductively coupled to said inductive coupling.

23. In combination, a section of railway track, a source of energy including the secondary winding of a transformer connected to the track rails at one end of the section, a winding of a transformer connected in series in the circuit which includes said secondary winding, a transmission circuit including two windings one of which is in inductive relation to the winding of the second mentioned transformer, and a circuit including an indicator lamp in inductive relation to the other of said two windings, the energy flow in said indicator lamp influenced by the presence and movement of a train on said railway track, said lamp having an appreciably higher degree of brilliancy when the train is at the end of the track section at which energy is supplied to the track section than when the train is at the opposite end of said track section.

24. The invention set forth in claim 23; characterized by a plurality of said indicator lamps for adjacent track sections being assembled to form a train indicator diagram.

25. A railway signaling system comprising a section of railway track, an automatic block signal and system for governing train movements on said track section, a signal receiver apparatus associated with said section, and an electric transmitter apparatus including train wheels and adapted to continuously transmit an indication to said receiver apparatus as to the position and progress of said train wheels on said section, said transmitter and receiver apparatus acting independent of said block signal.

26. In a train indication system, a section of railway track, an automatic block signal and system for governing movements of trains on said section, and an indicator lamp connected to said block signal system and without indication illumination when said section is not occupied by a train and with indication illumination when said section is occupied by a train, said indicator lamp having indication illumination of one value or another according as the train occupies one part or another of said track section, for indicating whether said train occupies one part or another of said track section, said indicator

lamp acting independent of said block signal.

27. A train indication system; characterized by a plurality of sources of energy impressed upon the track rails of a railway track, each source of energy having an inductive coupling included in series therewith, and an indicator lamp inductively coupled to each inductive coupling, each indicator lamp indicating the presence and movement of a car on said railway track.

28. A train indication system comprised of a section of railway track, a source of energy, transformers for supplying said energy to said track at a plurality of points, reactance elements connecting the rails of said track between the points of energy supply, and means for utilizing said energy to indicate the presence and movement of a train on said section of railway track.

29. A train indication system comprised of a section of railway track, a source of energy, transformers for supplying said energy to said track section at a plurality of points, an indication transmitter connected in series with each of said transformers, and an indicator lamp connected with each of said indication transmitters, for indicating the movement of a train on said section by variation in light emitted by said lamp.

30. A train indication system comprised of a section of railway track, a source of energy, transformers for supplying said energy to said track section at a plurality of points, an indication transmitter in series with the energy supply to the track rails of said track, and an indication receiver for each transmitter, each transmitter responsive controlling the corresponding receiver as a train moves on said section of railway track, each receiver indicating the movement of a train on said section of railway track.

31. A train indication system comprised of a section of railway track, a source of energy, transformers for supplying said energy to said track section at a plurality of points, indication transmitters inductively coupled to said supply, a transmission circuit for each transmitter, and remotely located indication means synchronously responsive to variations in the energy flow in said transmission circuit caused by the movement of a train on said section of railway track.

32. A train indication system comprised of a section of railway track, a source of energy, transformers for supplying said energy to said track at a plurality of points, indication transmitters inductively coupled to said track, and indication receivers including indicator lamps inductively coupled with said transmitters, said lamps energized from said source and with partial illumination when said track is unoccupied, said

illumination varying as a car moves on said track.

33. A train indication system comprised of a section of railway track, a source of energy, transformers for supplying said energy to said track at a plurality of points, indication transmitters inductively coupled to said track, and indication receivers connected to said transmitters, each receiver at 10 times indicating the presence of a train on said track and at times continuously indicating the movement of a train on said track.

34. A train indication system comprised 15 of a section of railway track, a source of

energy, transformers for supplying said energy to said track at a plurality of points, transformers in series with the secondary of the first mentioned transformers, transmission circuits in series with the secondary of the second mentioned transformers, a third transformer in series with each of said transmission circuits, and indicator lamps connected to the secondary of said third transformers. 20

Signed at New York in the county of New York and State of New York this 25th day of March A. D. 1924. 25
